PROTECTIVE COVERING FOR AIRFOILS

Thomas C. Harper, Akron, Ohio, assignor to The
B. F. Goodrich Company, New York, N. Y., a
corporation of New York

Application February 25, 1944, Serial No. 523,867

15 Claims. (Cl. 244—134)

1

This invention relates to protective coverings for airfoils and especially to coverings for preventing the accumulation of ice thereon.

In prior constructions of protective coverings in which a stretchable portion, between a central inflatable tube zone and an attaching margin, has been subjected to stretch for removing ice from such portion upon the inflation of each tube in said zone, the action of such coverings under some ice conditions of particular severity has not been effective to obtain full cleanliness of ice removal in the stretchable portion. Also, heavy ice caps over the inflatable tubes in the central zone have at times not been broken and removed with the full promptness and thoroughness desired. Very thin ice formations in this zone also have at times been difficult to remove. The restriction to inflation in the central tube zone by reinforcement, which has been provided therein to transmit the desired stretching force to the stretchable portion rearward of the tubes, has not been conducive to the most effective action in breaking and removing the ice cap. Also, the rapidly repeated stretching of the stretchable portion rearward of the tubes has under some ice conditions tended to craze or merely crack the ice repeatedly rather than break and remove it thoroughly from the surface of the covering.

While the ice conditions which have caused these difficulties are encountered perhaps infrequently, it is desirable that the protective covering be of a construction such as to operate with full effectiveness under all icing conditions.

To this end, an object of the invention is to provide for breaking and loosening effectively ice caps on the leading edge of an airfoil thereby facilitating the removal of such ice caps by the ambient flow of air.

Another object is to provide for thorough removal of the ice from a stretchable portion rearward of the immediate leading edge.

Another object is to provide for uniformity of stretch chordwise with little or no contraction spanwise of the protective covering, especially of stretchable or extensible portions rearward of an inflatable tube zone.

Further objects are to provide for imparting a substantial stretching force to the stretchable portion during inflation of a tube in the tube zone and for exerting little or no stretching force on such portion during inflation of another tube in such zone; and to provide for a condition of low installed stretch or elongation of the covering between the attaching margins thereof, while

2

effectively avoiding objectionable lifting of the covering from the airfoil surface.

Still further objects are to provide for maintaining the desired aerodynamic characteristics of the airfoil, especially during substantial stretching of the stretchable portion so as to obtain the ice-removing benefits of good laminar flow in this action; to provide durability, thinness and simplicity of construction and light-weight; and to provide for convenience of manufacture and installation and effectiveness of operation.

These and other objects and advantages of the invention will be apparent from the following description.

In the accompanying drawings which form a part of this specification and in which like numerals are employed to designate like parts throughout the same:

20 Fig. 1 is a perspective view of a protective covering or apparatus mounted on the leading edge of an airplane wing, and constructed in accordance with and embodying the invention, parts being broken away and in section,

25 Fig. 2 is a plan view from above of the covering before being installed on the wing, parts being broken away,

30 Fig. 3 is a cross-sectional view of the covering installed on the wing showing two cap-breaking tubes in the inflated condition with little or no stretching of the extensible portions rearwardly of such tubes,

35 Fig. 4 is a view like Fig. 3 but showing an associated stretching tube in the inflated condition stretching chordwise the rearward extensible portions, and

40 Fig. 5 is a view in an enlarged scale of a part of the extensible portion showing a kind of highly elastic fabric embedded therein, parts being broken away.

45 In the illustrative construction shown in Fig. 1, a protective covering 10 of elastic construction including resilient rubber or other rubber-like material is mounted on the leading edge of a wing 11 of an aircraft or airplane, the wing having a nacelle 12 housing a motor (not shown) driving a propeller 13 for propelling the airplane. Other airfoils, struts and other elements of the aircraft may be similarly provided as desired.

50 The protective covering 10 is mounted in a stretched condition chordwise of the wing 11 and secured to the wing skin along upper and lower attaching margins 14 and 15 extending spanwise of the wing. One result of the con-

struction described herein is that a materially lesser degree of stretch in the installed condition is feasible than in prior constructions. The attaching margins 14 and 15 may be secured to the wing as by attaching screws 16 extending through upper and lower marginal fairing strips 17, 17 and through the covering 10 and into the skin of the wing 11. The attaching margins 14 and 15 may have reinforcing strips or bead elements 18, 18 of stiff material such, for example, as metal wire included therein.

The covering 10 includes an outer layer or covering 20 of suitable resilient rubber-like material and preferably is of varying thickness, being relatively thin in section at a tube zone 21, for accommodating the different thicknesses of other parts such as extensible or stretchable portions 22 and 23 comprising the protective covering 10 while providing a smooth exterior contour thereby maintaining the desired aerodynamic characteristics of the wing 11. By virtue of the resiliency of the rubber material, such layer 20 resists effectively the abrasive action of foreign material in the airstream impinging thereagainst.

One or more and preferably a pair of inflatable cap-breaking tubes 24, 25 may be individually relatively small in cross-section as compared to an inflatable tube 26 which is larger in cross-section. The tubes 24 and 25 may be in superimposed relation with the tube 26 and disposed beneath that portion of the outer layer 20 overlying the tubes 24, 25 and may be positioned between the layer and the tube 26. The tubes 24, 25 and 26 are disposed in and extend along the tube zone 21, and the tubes 24 and 25 are positioned in chordwise series with their margins adjacent and preferably contiguous immediately at the frontal portion of the leading edge. A filler strip 30 of suitable resilient rubber-like material may be superimposed on the adjacent margins of the tubes 24 and 25 beneath the outer layer 20, as shown in Fig. 1, for aiding in obtaining the desired smooth exterior contour of the covering and for providing a strong juncture and anchorage.

The construction hereinabove described is advantageous in that substantially all the pulling stress chordwise in the covering in the installed condition is taken through the underlying tube 26 rather than through the overlying tubes 24 and 25 whereby the covering remains against the wing with little or no local lifting from the wing at the tube zone during inflation of the tubes 24 and 25. This action makes possible the avoiding of local entrapment of air beneath the covering at the tube zone 21 and its associated subsequent objectionable bulging of the extensible portions 22, 23 because of the flow of such entrapped air to such portions from the tube zone upon deflation of the tubes 24 and 25.

For inflating the tubes in the desired cyclic manner, connector means 27 in communication with the tubes may be provided at one end of the latter, as shown especially in Figs. 1 and 2. Fluid conduits 28 and 29 are connected to such connector means 27 and to suitable control apparatus (not shown) and to a source of air under pressure, which apparatus and source of air may be disposed, for example, within the fuselage of the aircraft.

The cap-breaking tubes 24, 25 which are mounted preferably immediately at the leading edge of the airfoil, have walls of relatively great stretchability as compared to that of the associated stretching tube 26. Such walls include in

the rubber thereof reinforcing material such as stockinet or other knitted or otherwise stretchable fabric, preferably of nylon or rayon, although cotton or other suitable material may be used. The nylon stockinet fabric is stretchable both circumferentially and longitudinally of the tube, which permits extensive stretching of the tube wall for expanding the covering locally at the tube zone 21 to break and loosen the heavy ice cap.

When the tubes 24 and 25 are inflated first in the cycle of inflation, preferably simultaneously, they tend to stretch outwardly from the wing 11 and to assume the relatively sharp curvature afforded by a semi-circular shape in section as shown in Fig. 3, by virtue of the uniform and high stretchability of the walls thereof. As the tubes 24 and 25 are thus highly distended they operate not only to crack an ice cap upon the leading edge, but also to shift the pieces of the cracked ice cap somewhat in the chordwise direction so as to subject the pieces to the force of the air flow, rather than permit such pieces to remain static in the frontal pressure zone. The outer portions of these cap-breaking tubes offer but little restraint against distension while the inner portions of the tubes are restrained by virtue of the stretched and tensioned condition existing in the installed covering between the attaching margins, the holding stress in such covering at the tube zone being taken largely by the tube 26 beneath tubes 24 and 25. As a consequence of the expanding action of the tubes 24 and 25, the surface of the outer layer 20 is stretched locally with low exertion of stretching force upon the rearward extensible portions 22 and 23.

The remaining tube 26, which like the pair of tubes 24, 25 is disposed in the tube zone 21, and preferably beneath such pair of tubes adjacent the wing 11, may have its opposite margins extending chordwise beyond the margins of the tubes 24 and 25 for facilitating the anchorage of the extensible portions 22, 23 thereto, as shown especially in Figs. 1 and 2, which anchoring arrangement also promotes freedom of expansion of the tubes 24, 25 and facilitates transmitting the holding stress in the covering to and through the material of such tube 26. The rubber wall of the tube 26 includes textile fabric material, preferably square-woven fabric, straight-laid, for limiting the expansion of the tube 26, such fabric being relatively inextensible as compared to the fabric included in the tubes 24, 25. Such expansion-limiting fabric reinforcement resist effectively the local stretching of the rubber wall and when inflated, the tube 26 assumes an outwardly curved shape of lesser sharpness of curvature than that of the tubes 24, 25 as shown in Fig. 4. This action further assists removal of any remaining broken pieces of the ice cap by the air flow and effectively imparts a relatively great stretching force to the extensible portions 22 and 23 and moves the latter portions outwardly from the wing 11 while maintaining the desired aerodynamic contour at the leading edge and avoiding objectionable turbulent flow of the ambient air across the wing 11.

Because a good aerodynamic shape is made possible, this construction is advantageous in cases where it is desired to use the inflatable structure for purposes of varying the aerodynamic characteristics of the wing, the inflation being such as to make possible a material increase in the wing area with or without a change in the wing camber.

The extensible or stretchable portions 22, 23 include the overlying portions of the outer rubber layer 20. Also, these portions 22 and 23 include inner rubber layers 31, 31 adjacent the wing skin and intermediate layers 32, 32 of highly elastic sheet fabric material embedded in and between the inner and outer layers, as shown especially in Figs. 1 and 5. This highly elastic fabric is stretchable chordwise and this result may be provided by a woven fabric having straight warp threads 32a with adjacent filling threads 32b, 32c highly twisted in reverse directions (Fig. 5), which fabric has extensive stretchability along the filling threads, disposed chordwise, and has little or no stretchability along the warp threads, disposed spanwise. By virtue of such woven construction the elastic fabric does not require the force of the resilient rubber with which it is impregnated and coated for returning to its original condition after being stretched, being in itself highly resilient. Thus, both the rubber and the fabric are better able to resist the development of objectionable permanent set.

The uniformity of stretching afforded by the elastic fabric contributes to effective ice removal by imparting the stretching forces uniformly to and throughout the extent of the outer surface at the extensible portions 22, 23 thereby stretching the material beneath as well as around the bases or seats of the adhering ice particles and loosening the same, which action is not fully available in an unreinforced rubber sheet that tends to transmit a stretching force around an ice particle rather than through its seat. The elastic fabric is advantageous also in giving added resistance throughout its coverage to objectionable lifting of the covering in any part of its extent. Also, it is not subject to objectionable contraction spanwise of the extensible portions.

For the construction shown front marginal portions of the intermediate fabric layers 32, 32 are overlapped with and are secured as by rubber to the margins of the stretching tube 26 for anchorage thereto to facilitate stretching the extensible portions 22 and 23 when such tube is inflated, with little or no stress on the walls of the cap-breaking tubes 24, 25 and to facilitate transmitting the static holding stress in the covering largely through the material of the tube 26. The elastic fabric extends chordwise to permit folding the fabric around the respective beads 18, 18 at the attaching margins 14 and 15 for holding the beads and receiving the attaching screws 16. An offset arrangement is made possible for a flush mounting of the fairing strips 17, 17.

For venting the protective covering 10 to prevent objectionable lifting of portions of such covering under the aerodynamic forces at the leading edge, the inner layers 31, 31 of the extensible portions 22, 23 may be provided with a multiplicity of spaced-apart rectilinear rib elements 33, 33 extending spanwise along the inner faces thereof for defining venting channels. Venting grooves 34 extending chordwise and being in communication with the channels may have venting apertures 35, 35 therein disposed along lines spanwise at corresponding chordwise positions, which apertures are in communication with the outer air. The venting channels may also be in communication with the outer air at the ends of the protective covering 10. This subject matter of the channels and grooves for venting action is set forth more fully in the copending application of Willson H. Hunter and William C.

Green, Serial No. 482,536, filed April 10, 1943, now Patent No. 2,421,621.

The fabric and rubber parts of the covering 10 are united by vulcanization and heat under pressure.

The construction herein described eliminates to a large extent the need for fillets; and eliminates the necessity for special tear-resisting strips, sponge-rubber fillers and special fabric reinforcements at the attaching margins. It also makes possible a thinner, lighter, and more nearly uniform construction. Manufacture is facilitated and a product of improved aerodynamic cleanliness is provided.

15 In the operation of the protective covering 10, it is desirable that the pair of inflatable tubes 24, 25 be inflated first in the cycle and simultaneously by admitting the air under pressure through the conduit 28 and connector means 27. These tubes then distend outwardly to a substantially semi-circular shape in cross-section in the manner shown in Fig. 3, the walls of such tubes stretching locally to a relatively great extent within themselves by virtue of the stretchable action of the nylon fabric, and the outer portions of these tubes under inflation spread apart somewhat due to the curvature at the leading edge region, all of which assists in breaking ice caps. While the outer layer 20 at the tube zone 21 is stretched extensively, such distending and stretching action of the tubes 24 and 25 exerts little or no stretching force upon the adjacent extensible portions 22, 23, which portions and the inner part of the covering at the tube zone 21 remain against the wing with negligible lifting therefrom during this phase of the cycle of inflation by virtue of the construction of the covering as described hereinabove. The stretching of the tubes 24 and 25 is found to be highly effective at the immediate 20 leading edge region in cracking and loosening the ice cap even though the ice cap be heavy. However, such inflation need have little or no effect on rearward ice formations on the extensible portions 22 and 23, which ice formations are taken care of during the inflation of the tube 26.

40 For the removal of the sheet-like ice formations which extend rearwardly and adhere to the extensible portions 22, 23, the pair of tubes 24, 25 is deflated and the associated stretching tube 26 is then inflated by air under pressure flowing through the conduit 29 and the connector means 27. Since the wall of the inflatable tube 26 includes the expansion-limiting reinforcing fabric which is relatively inextensible, such tube 26 distends outwardly and assumes an expanded condition substantially as shown in Fig. 4. This action is effective in imparting a relatively great stretching force to the extensible portions 22, 23 in the chordwise extent substantially uniformly throughout their spanwise extent to break and loosen the ice formations on the portions 22, 23. The highly elastic fabric 32, 32 in such portions transmits the imparted stretching forces uniformly to the outer layer 20 whereby such outer layer stretches under as well as around the bases of the adhering ice particles. In this manner the ice on these portions 22, 23 is broken into pieces, which facilitates the thorough and prompt removal of such pieces by the nearly laminar flow of air over these portions of the covering.

60 The effectiveness of this ice removal in the portions 22, 23 is found to be greater than if these portions were to be stretched more frequently, as for each tube inflation, but to a lesser extent of stretch than is here obtained, and the im-

proved ice-removing action is contributed to also by the greater uniformity of stretchability of this portion made possible by the elastic fabric reinforcement above described.

The construction herein described also permits installing the covering with low percentage of static stretch between the attaching margins thereby making possible greater dynamic stretching of the stretchable portions than has been feasible in prior constructions, which result is advantageous in promoting the thorough and prompt removal of ice formations on these portions.

Still another feature of the protective covering 10 is that, when the stretching tube 26 is in the inflated condition, the covering assumes a shape in section such that the general airfoil contour at the leading edge is maintained even though the chordwise extent of the airfoil is increased by the movement of the covering outwardly from such leading edge. Maintaining the airfoil contour promotes smooth flow of air about the covering and wing during the operation of such covering thereby maintaining to a high degree the aerodynamic characteristics of the wing.

Variations may be made without departing from the scope of the invention as it is defined in the following claims.

I claim:

1. Apparatus for preventing the accumulation of ice on the leading edge of an airfoil, said apparatus comprising a resilient covering for said leading edge comprising an expansible zone including an inflatable portion and a second inflatable portion outwardly overlying the first said inflatable portion, an extensible portion between said zone and a margin of the covering, said extensible portion being stretchable substantially uniformly in the chordwise direction and being substantially inextensible in the spanwise direction, the first said inflatable portion including stretch-resisting material and being constructed and arranged for imparting upon inflation a stretching force to said extensible portion, the said second inflatable portion including material of relatively high stretchability and being constructed and arranged for local inflation of said second inflatable portion by virtue of the high stretchability thereof without exerting substantial stretching force on said extensible portion.

2. Apparatus for preventing the accumulation of ice on the leading edge of an airfoil, said apparatus comprising a covering including resilient rubber-like material for said leading edge having a tube zone and an extensible portion between said zone and a margin of the covering, an inflatable tube in said zone, and a pair of inflatable tubes arranged in series chordwise and superimposed on the first said tube in said zone, adjacent margins of said pair of tubes being anchored to the first said tube for resisting outward movement of said adjacent margins relative to said leading edge upon inflation of said pair of tubes, the first said tube having an expansion-limiting reinforcement therein effective upon inflation thereof to impart a stretching force to said extensible portion, and said pair of inflatable tubes having walls of relatively great stretchability as compared to the first said tube for local stretching upon inflation thereof with relatively low exertion upon said extensible portion of stretching force as compared to the first said tube and with minimum outward movement of said adjacent margins.

3. Apparatus for preventing the accumulation

of ice on the surface of an airfoil, said apparatus comprising a covering of resilient rubber-like material and an elastic fabric embedded in said material and continuous and substantially coextensive with the dimension of said covering in one direction, said fabric comprising warp elements extending in said one direction of the covering and filling elements disposed crosswise thereof, adjacent filling elements being highly twisted in reverse directions whereby said fabric is substantially inextensible in said one direction and highly stretchable crosswise thereof and is substantially noncontractile in said one direction under the crosswise stretching.

4. Apparatus for preventing the accumulation of ice on the leading edge of an airfoil, said apparatus comprising a protective covering including resilient rubber-like material for said leading edge having a tube zone extending spanwise of the covering and an extensible portion extending spanwise between said zone and a margin of the covering, said extensible portion comprising sheet elastic fabric material substantially coextensive with the spanwise dimension of said covering, said fabric material having relatively great stretchability in the chordwise direction and being relatively inextensible in the spanwise direction, an inflatable tube in said zone having a stretch-resisting fabric material reinforcement therein effective upon inflation of the tube to impart a stretching force to said extensible portion, a second inflatable tube in said zone outwardly overlying and anchored to the first said inflatable tube, said second inflatable tube having a wall including stretchable fabric material of relatively great stretchability as compared to the first said tube for local stretching circumferentially upon inflation of the second tube with relatively low exertion of stretching force as compared to the first said tube upon said extensible portion, means for attaching said covering at said margin, and means for inflating the tubes.

5. Apparatus for preventing the accumulation of ice on the leading edge of an airfoil, said apparatus comprising a covering of resilient rubber-like material for said leading edge having spaced-apart extensible portions including attaching margins and a tube zone intermediate said extensible portions, said extensible portions comprising elastic fabric substantially stretchable in the chordwise direction and relatively inextensible in the spanwise direction, an inflatable tube of substantially inextensible fabric material in said tube zone beneath said covering effective upon inflation to impart stretching force to said extensible portions, a pair of adjacent inflatable tubes in said tube zone beneath said covering superimposed on said inflatable tube, the pair of inflatable tubes comprising fabric material having relatively great stretchability as compared to the fabric material of the first said tube for local stretching upon inflation thereof with relatively low exertion of stretching force as compared to the first said tube upon said extensible portions, means for attaching said covering at said margins, and means for inflating the tubes.

6. Apparatus for preventing the accumulation of ice on the leading edge of an airfoil, said apparatus comprising a covering including resilient rubber-like material for said leading edge, said covering comprising an expansible zone extending in one direction of said covering which expansible zone includes an inflatable portion, said covering comprising also an extensible portion

extending in said direction along said zone between said zone and a margin of the covering and including substantially all-over sheet elastic fabric material continuous and substantially coextensive with the dimension of said covering in said direction, said fabric material comprising substantially non-stretchable elements of filamentary material extending in said direction and stretchable elements of filamentary material extending crosswise of said direction so as to be stretchable crosswise of said direction and substantially noncontractile in said direction under the crosswise stretching, and means for attaching said covering at said margin.

7. Apparatus for preventing the accumulation of ice on the leading edge of an airfoil, said apparatus comprising a covering of resilient rubber-like material for said leading edge, said covering comprising an inflatable tube having stretch-resisting fabric material therein extending in one direction of said covering, a second inflatable tube of fabric material of relatively high stretchability as compared to that of said stretch-resisting fabric material extending in said one direction of the covering and outwardly overlying the first said inflatable tube, and an extensible portion extending in said direction along said tubes between said tubes and a margin of said covering, said extensible portion including substantially all-over sheet elastic fabric material substantially coextensive with the dimension of said covering in said direction and continuously secured along one margin of said extensible portion to the first said inflatable tube, said sheet elastic fabric material comprising warp elements extending in said direction of the covering and filling elements disposed crosswise of said direction, adjacent filling elements being highly twisted in reverse directions, said sheet elastic fabric material being stretchable crosswise of said direction and substantially noncontractile in said direction under the crosswise stretching, and means for inflating said tubes whereby the first said tube under inflation is effective to impart substantially uniform stretching force to said extensible portion substantially throughout the extent of said portion.

8. Apparatus for preventing the accumulation of ice on the leading edge of an airfoil, said apparatus comprising a resilient covering for said leading edge comprising a spanwise-extending expandable portion including an inflatable passage and a second inflatable passage outwardly overlying the first said passage, and a spanwise-extending extensible portion including substantially all-over sheet elastic fabric material therein between said expandable portion and a margin of the covering, said sheet elastic fabric material being stretchable substantially uniformly in the chordwise direction and being substantially inextensible in the spanwise direction, the first said inflatable passage having a stretch-resisting reinforcement therein effective upon inflation of the passage to impart relatively great stretching force to said extensible portion, and said second inflatable passage having an outer wall including material of relatively high stretchability as compared to the first said inflatable passage for local inflation of said second inflatable passage by virtue of the high stretchability of said outer wall without exerting substantial stretching force on said extensible portion.

9. Apparatus for preventing the accumulation of ice on the leading edge of an airfoil, said apparatus comprising a resilient covering for said

leading edge comprising an expandable zone including an inflatable portion and a second inflatable portion outwardly overlying the first said inflatable portion, and an extensible portion between said zone and a margin of the covering, the first said inflatable portion including stretch-resisting material and being constructed and arranged for imparting upon inflation a stretching force to said extensible portion, the said second inflatable portion including material of relatively high stretchability as compared to said stretch-resisting material and being constructed and arranged for local inflation of said second inflatable portion by virtue of the high stretchability thereof without exerting substantial stretching force on said extensible portion.

10. Apparatus for preventing the accumulation of ice on the leading edge of an airfoil, said apparatus comprising a resilient covering for said leading edge comprising an expandable zone including an inflatable tube and a second inflatable tube outwardly overlying the first said inflatable tube, and an extensible portion extending along substantially the entire length of said tubes between said zone and a margin of the covering, said extensible portion being stretchable substantially uniformly in the direction toward said margin throughout said length, the first said inflatable tube including stretch-resisting material in the wall thereof and being constructed and arranged for imparting upon inflation a stretching force to said extensible portion, the said second inflatable tube including material in the wall thereof of relatively high stretchability as compared to that of said stretch-resisting material and being constructed and arranged for local inflation of said second inflatable tube by virtue of the high stretchability thereof without exerting substantial stretching force on said extensible portion.

11. Apparatus for preventing the accumulation of ice on the leading edge of an airfoil, said apparatus comprising a resilient covering for said leading edge comprising a spanwise-extending expandable zone including an inflatable tube and a second inflatable tube outwardly overlying the first said inflatable tube, and a spanwise-extending extensible portion between said zone and a margin of the covering, the first said inflatable tube including stretch-resisting fabric material and being constructed and arranged for imparting upon inflation a stretching force to said extensible portion, the said second inflatable tube including fabric material of relatively high stretchability circumferentially of such tube as compared to that of said stretch-resisting fabric material and being constructed and arranged for local inflation and circumferential stretching of the outer wall of said second inflatable tube by virtue of the high stretchability thereof without exerting substantial stretching force on said extensible portion.

12. Apparatus for preventing the accumulation of ice on the leading edge of an airfoil, said apparatus comprising a resilient covering for said leading edge, said covering comprising an expandable zone including an inflatable tube extending in one direction of said covering and a second inflatable tube extending in said direction and outwardly overlying the first said inflatable tube, and an extensible portion extending in said direction along said zone between said zone and a margin of the covering, the first said inflatable tube including stretch-resisting fabric material in the wall thereof and being constructed and arranged for imparting upon inflation a stretching

force to said extensible portion, the second said inflatable tube including fabric material in the wall thereof of relatively high stretchability as compared to that of said stretch-resisting fabric material and being constructed and arranged for local inflation of said second inflatable tube by virtue of the high stretchability thereof without exerting substantial stretching force on said extensible portion, and said extensible portion including substantially all-over sheet elastic fabric material substantially coextensive with the extent of said tubes in said direction, said sheet elastic fabric material comprising warp elements extending in said direction of the covering and filling elements disposed crosswise of said direction, adjacent filling elements being highly twisted in reverse directions whereby said sheet elastic fabric material is highly stretchable crosswise of said direction of the covering and substantially noncontractile in said direction under the crosswise stretching.

13. Apparatus for preventing the accumulation of ice on the leading edge of an airfoil, said apparatus comprising a covering of resilient rubber-like material for said leading edge having a tube zone and an extensible portion between said zone and a margin of the covering, means for attaching said covering at said margin, an inflatable tube of stretch-resisting fabric material in said zone, and a pair of inflatable tubes each relatively small as compared to the first said inflatable tube extending in side-by-side relation between the adjacent margins of the first said inflatable tube in said zone and outwardly overlying the first said inflatable tube, the first said inflatable tube being constructed and arranged for imparting upon inflation a stretching force to said extensible portion, and said pair of inflatable tubes including fabric material in the walls thereof having relatively great stretchability as compared to that of said stretch-resisting fabric material and being constructed and arranged for local inflation of said pair of inflatable tubes by virtue of the high stretchability thereof without exerting substantial stretching force on said extensible portion.

14. Apparatus for preventing the accumulation of ice on the leading edge of an airfoil, said apparatus comprising a protective covering including resilient rubber-like material for said leading edge, said covering having an extensible portion extending in the spanwise direction and an extensible portion extending in the said direction between said extensible portion and a spanwise-extending margin of the covering, said extensible portion comprising substantially all-over

sheet elastic fabric material having spanwise-extending substantially non-stretchable elements of filamentary material and chordwise-extending stretchable elements of filamentary material so as to have relatively great stretchability in the chordwise direction and be substantially non-contractile in the spanwise direction under the chordwise stretching, said sheet elastic fabric material being continuous and substantially coextensive with the spanwise dimension of said covering, means for attaching said covering at said margin, and means for expanding said extensible portion and stretching said extensible portion.

15. Apparatus for preventing the accumulation of ice on the leading edge of an airfoil, said apparatus comprising an elastic covering including resilient rubber-like material for said leading edge, said covering comprising an underlying portion of substantially inextensible textile fabric extending spanwise and an underlying extensible portion of substantially all-over sheet elastic fabric secured to and extending chordwise from the first said underlying portion to an attaching margin of said extensible portion spaced therefrom, said sheet elastic fabric extending continuously and substantially coextensive with the spanwise dimension of said covering, said sheet elastic fabric comprising stretchable elements of filamentary textile material extending chordwise and substantially non-stretchable elements of filamentary textile material extending spanwise so as to be stretchable in the chordwise direction and substantially noncontractile in the spanwise direction under the chordwise stretching, and means for distending at least a part of said covering and stretching said extensible portion.
